UNITED STATES PATENT OFFICE.

CORNELIUS KUHLEWIND, OF KNOXVILLE, PENNSYLVANIA.

PRESSURE-RELIEVING DEVICE.

SPECIFICATION forming part of Letters Patent No. 656,141, dated August 14, 1900.

Application filed December 22, 1899. Serial No. 741,208. (No model.)

To all whom it may concern.

Be it known that I, CORNELIUS KUHLEWIND, of Knoxville borough, in the county of Allegheny and State of Pennsylvania, have 5 invented a new and useful Improvement in Pressure-Relieving Devices, of which the following is a full, clear, and exact description, reference being had to the accompanying drawings, forming a part of this specification, 10 in which—

Figure 1 is a top plan view of my improved relief device. Fig. 2 is a sectional side elevation. Fig. 3 is a vertical cross-section. Fig. 4 is a partial plan view showing a modified 15 form, and Fig. 5 is a broken side elevation of Fig. 4.

My invention relates to devices for relieving the pressure upon rolls or similar apparatus when this pressure exceeds a determined limit, and is designed to provide a device for this purpose, containing movable parts provided with inclined faces, which shall wear evenly and uniformly under service, which may be cheaply and easily constructed, 25 and which will give efficient relief action.

In the drawings, referring to Figs. 1, 2, and 3, 2 represents a roll-breaker having a cylindrical socket containing a lower rotatable plug 3, which is provided with a set of upper 30 inclined wedge-faces 4, forming curved ratchet-teeth. The lower end of this plug is made in the form of an eccentric hub 5, as shown in dotted lines in Fig. 1, and fitting the periphery of this hub is a loose push-block or link 6, having a curved extension 7, which fits in a corresponding recess in a 35 wedge-block 8, which slides horizontally within a laterally-extending socket of the breaker. This horizontally-movable block 8 engages a vertically-movable wedge-block 9, the two 40 having coacting inclined faces, and the block 9 is provided with a central square hole in which fits a locking-block 10, having a locking extension 11, which fits within a recess in the 45 block 8. The hole through the block 9 opens into a recess in its back portion, within which fits the head 12 of a vertically-movable slide 13. This head is provided with an inclined face bearing upon a corresponding face on the 50 locking-block and is recessed to allow a certain range of upward movement before it engages a projection 14 upon the block 9, and

thereby lifts this block. The body of the slide 13 projects over the upper end of the wedge-block 9, and the outer reduced portion 15 of 55 this body is provided with a depending stem 16, which passes down through a cross-head 17 and is provided at its lower end with a nut. At the sides of the slide 13 brackets 18 are secured to the breaker-body and in their 60 outer ends are provided sockets for spiral springs 19, which surround stems 20, secured to the brackets. These stems extend down through the cross-head 17, and their lower ends are provided with nuts, as shown in Fig. 65 2. The springs 19 bear upon the cross-head and through the stem 16 draw down the vertical slide and hold the parts in their normal position.

To rotate the plug 3 when excessive pressure is exerted, I provide a corresponding cylindrical plug 21, having curved wedge-faces forming teeth, which fit upon the teeth of the plug 3. The plug 21 is secured to an upper square head which fits in a corresponding square socket in a cover-plate 22 and is normally held in the upper portion of this socket. A spring 23 is secured in central registering holes in the plugs and tends to turn the lower plug to cause the teeth to engage each other. The side portions of the head 22 are beveled or cut inwardly at 24 and engage corresponding faces upon the outwardly-movable blocks 25. These blocks are provided at their outer ends with inclined 85 faces 26, which coact with similar faces upon longitudinally-movable blocks 27, normally pressed forward by springs 28. The supplemental spring wedge system thus provided acts to lift the upper plug slightly from the 90 lower one and is arranged to be actuated by the ordinary working pressure of the rolls. When the piece enters the pass in the rolls and the pressure is brought upon them, this supplemental wedge system will be actuated 95 and the upper plug 21 moved down into contact with the lower turning plug 3, being maintained in this position during the ordinary operation of the mill. By this system the jar and vibration incident to the entering 100 of the piece in ordinary mills are largely done away with.

In order to afford means for relieving the pressure by hand whenever desired I pivot-

ally connect the central stem 16 by a lever 29 with a hand-lever 30, pivoted to a bracket at 31. The lever 29 is fulcrumed at 32 and the pin at its upper end enters a slot 35 in the lever, so that when the excess pressure is automatically relieved this pin will move downwardly in the slot and leave the hand-lever stationary. When, however, it is desired to relieve the rolls by pressing down upon the hand-lever, the lever 29 will move the cross-head 17 upwardly, and thereby first release the locking-block by drawing up the slide and thereafter pull upwardly the main wedge-block 9 by the engagement with it of the head of the slide.

In the operation of the device the parts maintain their ordinary position, with the teeth of the two plugs in contact, until excessive pressure is caused, as by a piece sticking in the rolls. When this occurs, the upper plug will be moved down, and being held against rotation its inclined teeth will cause a turning movement of the lower plug 3, the eccentric hub portion of which will move the 25 push-block, and thereby force the locking-blocks back within the wedge 9, the slide 13 moving upwardly against the pressure of the springs 19. The wedge-block 9 also moves upwardly, the block 8 being forced out horizontally in its socket. The pressure upon the roll is thus relieved, and as soon as the excessive pressure is removed the parts will resume their normal position, the spring between the plugs aiding in turning the lower 35 plug and bringing the parts back into their normal place.

In the form of Figs. 4 and 5 the construction is the same as that of the preceding figures, excepting that instead of the wedge system acted upon by the push-block I provide a screw system which gives substantially the same result. In this form the head 7' of the push-block 6', which is acted upon by the eccentric hub 5', acts upon the inner head 34 of a screw-threaded stem 35, which extends outwardly through the breaker. Surrounding this stem within the breaker-body is a hollow shaft 36, which is provided with an inner screw-thread engaging the screw-threaded 45 stem and with outer square screw-threads 37 engaging corresponding threads in the recess of the breaker therefor. To the outer end of this hollow shaft, which forms a nut for the stem, is secured a lever 38, provided with a 50 counterweight 39. The head 34 of the inner stem being square, this stem is held against rotation, and consequently when the excess pressure is brought to bear the head 34, being forced out, will cause the hollow shaft 36 to 55 turn and lift the lever against the action of

its counterweight. As soon as the excess pressure is removed the counterweight will move the lever down and turn the hollow shaft or nut, the head of the stem moving in and the parts resuming their normal position. 65

The advantages of my invention result in part from the use of the inclined teeth between the plugs or wedge-blocks, which give uniform wear and long life to the device, and, further, from the simplification and compactness of the device. 70

Many variations may be made in the form and arrangements of the parts without departing from my invention.

I claim—

1. In a relief device, a vertically-movable element, a rotatable element coacting therewith, and a yielding device arranged to hold the rotatable element against turning; substantially as described. 75

2. In a relief device, a vertically-movable element held against rotation and having an inclined face, a rotatable block having a corresponding inclined face, and a yielding pressure device arranged to resist turning of the 80 rotatable block; substantially as described. 85

3. In a relief device, a reciprocating block, having an inclined face, a rotatable block having a corresponding face coacting therewith, a cam or eccentric arranged to be actuated by 90 the turning of the rotatable block, and a yielding pressure device coacting with the cam; substantially as described.

4. A relief device for rolls, having a vertically-movable angular block guided in an angular socket, and having inclined teeth, a rotatable plug having correspondingly-inclined teeth, an eccentric or cam upon the rotary plug, and a yielding pressure device acted upon by the cam; substantially as described. 95

5. In a relief device, a reciprocating block held against rotation, a rotary element arranged to be turned by reciprocation of the block, a yielding pressure device arranged to be actuated by the turning of the rotary element, and hand mechanism arranged to relieve the yielding pressure device; substantially as described. 100

6. In a relief device, a vertically-movable plug having inclined teeth, a rotary plug having corresponding teeth, said rotary plug having a cam or eccentric, and a spring-pressed wedge system arranged to be actuated by the cam or eccentric; substantially as described. 110

In testimony whereof I have hereunto set my hand.

CORNELIUS KUHLEWIND.
